UNITED STATES PATENT OFFICE.

EDSON FITCH SPINNER, OF AVA, ILLINOIS.

PLOWSHARE-FASTENER.

No. 902,770.

Specification of Letters Patent.

Patented Nov. 3, 1908.

Application filed April 4, 1908. Serial No. 425,192.

To all whom it may concern:

Be it known that I, EDSON FITCH SPINNER, a citizen of the United States, residing at Ava, in the county of Jackson and State 5 of Illinois, have invented new and useful Improvements in Plowshare-Fasteners, of which the following is a specification.

This invention relates to plows, and more particularly to plow share fasteners, and has 10 for an object to provide a device of this character for detachably joining the plow share to the plow, and to permit the ready attachment and detachment of the same when desired without the use of bolts or the 15 like.

Other objects and advantages will be apparent as the nature of the invention is better disclosed, and it will be understood that changes within the scope of the claims may 20 be resorted to without departing from the spirit of the invention.

In the drawing, forming a portion of this specification, and in which like numerals of reference indicate similar parts in the several views.—Figure 1 is a perspective view 25 partly in section, Fig. 2 is a perspective view of the hook, Fig. 3 is an end view of the cam lever.

In the drawing, there is shown a malleable iron casting 5 to which the beam A, as shown in dotted lines, is secured. While the casting is preferably formed from malleable iron, it will of course be understood that the same may be formed from wrought-iron or 30 steel. The casting is provided at its forward edge with a plurality of angularly disposed ears 6 in which are formed passages 7 for receiving rivets or similar fastening means to be engaged with the mold board 40 8, as shown in Fig. 1 of the drawing. At the forward end, the casting is extended downwardly and outwardly to form an ear 9 which is forked as indicated at 10 to engage a headed pin 11 projecting laterally 45 from one side of the landside or bar 12. A member 13 is pivotally connected at 14 to the casting 5 and is provided at its lower end with a hooked portion 14' for engagement with a headed pin 15 projecting from

one side of said landside or bar previously described.

The casting is provided with a horizontally disposed pin 16 upon which a cam or eccentric 17 is mounted, the same being provided with a suitable operating lever 18. 55 The cam or eccentric is disposed in a cam slot 19 formed in the member 13, as shown. The mold board is provided with a strap or lug upon its under side and is adapted to engage the share to keep the meeting edges of 60 said mold board and said share in alinement. The mold board, and the share are connected by a suitable brace member 20.

Assuming the plow to be in an inverted position and resting upon the beam A, and it is desired to move the share, it is simply necessary to push the lever 18 in a downward direction, as indicated by the dotted lines shown in Fig. 1 of the drawing, thus throwing the member 13 in the position shown in 65 dotted lines in the same figure to disengage the hooked portion at the lower end of said member with a pin 15, whereupon, the share may be lifted at the rear end until the forward portion of the casting is disengaged 75 from the pin 11. The device is extremely simple in construction, may be manufactured at a relatively low figure, effectively serves as means to permit a ready attachment of a share to a mold board, and as is obvious, the device can be constructed in a manner whereby it may be applied to plows 80 of various construction without materially changing the same.

I claim:—

1. The combination with a plow and its mold board, of a share detachably engaged adjacent to its forward end with said mold board, and a cam actuated locking element located beneath the mold board and adapted 90 to engage the landside of the share.

2. The combination with a plow beam, of a casting secured to the beam, a mold board secured to the casting, a share detachably connected at the forward end of said casting, 95 a swinging member detachably connected to the landside of the share, and cam operated means for operating said swinging member,

3. The combination with a plow beam, of a casting secured thereto, said casting having a hooked forward portion, a mold board carried by the casting, a share and its landside, a pin carried by the landside for receiving the hooked portion of the casting, a pivotally mounted member carried by the casting having a hooked lower end, a pin carried by the landside for receiving the hooked end, and a cam carried by the casting for controlling the movement of said member. 10
